US0D1059505S

(12) United States Design Patent (10) Patent No.: US D1,059,505 S
(45) Date of Patent: * Jan. 28, 2025

(54) EXERCISE MACHINE

(71) Applicant: SHENGCHEN TRADING CO., LIMITED, Hong Kong (CN)

(72) Inventor: Bosheng Hu, Shanghai (CN)

() Term: 15 Years

(21) Appl. No.: 29/966,571

(22) Filed: Oct. 3, 2024

(51) LOC (15) Cl. 21-02

(52) U.S. Cl.

USPC D21/671

(58) Field of Classification Search

CLAIM

The ornamental design for an exercise machine as shown and described.

DESCRIPTION

FIG. 1 is a front, right and top perspective view of an exercise machine showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

1 Claim, 8 Drawing Sheets
